HEATING DEVICE

Filed Oct. 23, 1929

Inventor:
Earle E. Lee,
By *Sympathetic Lee, Christian, Miles*,
Attys.

UNITED STATES PATENT OFFICE

EARL E. LEE, OF ZION, ILLINOIS

HEATING DEVICE

Application filed October 23, 1929. Serial No. 401,717.

This invention relates to improvements in heating devices and, more especially, such a device adapted for warming the oil in the crank case of an automobile.

5 My heating device is an improvement on that shown in Patent No. 1,356,524 of October 26, 1920, granted to A. H. Grange.

The principal feature of my invention is the provision of means in connection with 0 such a heater to permit the same to be operated by the starting and lighting battery of an automobile, which is ordinarily six volts, or by the common house lighting circuit which is ordinarily one hundred and ten 5 volts. Because of the great difference in voltage of such circuits, it is not feasible to operate a single heater from both unless special provision is made to permit this. In many instances, when such a heater is most 10 needed, the car is standing in a garage where a power line is available. In such cases, the car battery can be spared if current from the power line can be used. If the heater can be operated only by a one hundred and ten 15 volt current, however, there may be times when current from the car battery is the only power available; and in such cases, the heater is useless unless six volts can be used 20 to operate it. By the use of my invention, either source of current can be used.

Another feature is the provision of improved means for mounting the heater in the 25 crank case.

Other features and advantages of my invention will appear more fully as I proceed 30 with my specification.

In that form of device embodying the features of my invention shown in the accompanying drawing—

40 Figure 1 is a view in side elevation showing a part of the crank case of an automobile broken away; Fig. 2 is a view in perspective of the heater removed from the crank case, showing portions in section; and Fig. 3 is a 45 wiring diagram.

As shown in the drawing, 1 indicates a heating element which may be of almost any form and is here shown as rectangular and flat. The heating element is mounted in the 50 lower part of the crank case 2 of the internal

combustion engine, preferably close to the oil strainer 3, the latter having the usual pipe connection 4 to the oil pump (not shown).

The heating element may be held in place 55 in any suitable manner. For example, I have here shown it as provided with a pipe 5, the end of which is threaded, as indicated by 5*. The end of the pipe 5 is inserted through a suitable hole in the wall 2* of the crank case and held firmly by the two lock nuts 6, 6 60 screwed tightly against the wall, one on the outside and one on the inside. Suitable packing (not shown) may be used to assist in making an oil-tight joint.

In order to permit the heater to be operated 65 by either a six volt or a one hundred and ten volt current, the same is provided with two resistance elements, 7 and 8 with separate circuits. The element 7, for example, may be adapted for six volts and the other for one 70 hundred and ten volts. The elements may be made of any suitable material, for example, nichrome ribbon or wire. The elements may be separated by a sheet of mica 9 and similar sheets 10, 10, may be provided on the outside 75 to insulate the elements from the casing 1* of the element.

The tube 5 may serve as a conduit from the leads to the resistance elements. The wires 11, 11 from the element 8 may be 80 provided with an Edison type plug 12 adapted for insertion in the usual socket 13 of a power lighting circuit. The wires attached to the element 7 are indicated by 14 and 15, the former leading to ground 16 and the latter to a suitable switch 17 which, in turn, may be supplied with current through the wire 18 connected to the ammeter A of the car. In the case shown, the ammeter is supplied 85 in the usual manner from the car battery 19.

While I have shown and described certain 90 embodiments of my invention, it is to be understood that it is capable of many modifications. Changes, therefore, in the construction and arrangement may be made 95 without departing from the spirit and scope of my invention as disclosed in the appended claim, in which it is my intention to claim all novelty inherent in my invention as 100

broadly as permissible, in view of the prior art.

What I regard as new, and desire to secure by Letters Patent, is:

In combination with an internal combustion motor; a crank case for the motor having a hole in one side wall, said hole being spaced above the bottom of the crank case; an electric heating element in the crank case arranged adjacent the bottom thereof and provided with a tubular member extending through the hole in the wall, said tubular member having sufficient length to space the heating element a substantial distance from the side wall with the hole therein; means for retaining the tubular member in position including a lock nut thereon adapted to be screwed against the side wall of the crank case; an electric resistance element in the heating element; and conducting wires connected to the resistance element, said wires passing through the tubular member to the outside of the crank case.

In witness whereof, I have hereunto set my hand and seal this 21st day of October, 1929.

EARLE E. LEE.
